UNITED STATES PATENT OFFICE.

JOHN HAZLETT, OF KINGSTON, CANADA.

STEAM-BOILER.

SPECIFICATION forming part of Letters Patent No. 544,619, dated August 13, 1895.

Application filed June 8, 1895. Serial No. 552,142. (No model.) Patented in Canada June 18, 1894, No. 46,372.

To all whom it may concern:

Be it known that I, JOHN HAZLETT, a citizen of the Dominion of Canada, residing at Kingston, in the Province of Ontario, Canada, have 5 invented certain new and useful Improvements in Steam-Boilers, (for which I have obtained a patent in Canada, June 18, 1894, No. 46,372;) and I do declare the following to be a full, clear, and exact description of the invention, such as will enable others skilled in the art to which it appertains to make and use the same.

This invention relates to improvements in steam-boilers for either stationary or marine engines, and the novelty and many advantages will appear from the following description and claims, when taken in connection with the annexed drawings, in which—

Figure 1 is a front view with the smoke-stack broken away. Fig. 2 is a similar view of the rear. Fig. 3 is a vertical sectional view taken in the plane indicated by the dotted line α α on Fig. 1, and Fig. 4 is a vertical cross-sectional view.

25 Referring by letter to said drawings, A indicates the front and B the rear water-leg.

C indicates the steam-drums, there being two here illustrated, although in some cases but one drum need be employed. The water-legs comprise an inner wall a and an outer wall b , and these outer walls, which are respectively formed from single plates of metal, extend up and constitute the heads or ends of the drums, as better shown in Fig. 3 of the 35 drawings, for a purpose which will presently appear. The inner walls a of the water-legs are pierced, as shown at c , to receive the opposite end of the tubes D. These tubes are arranged upon an incline from front to rear, 40 so as to aid in the circulation of the water, and the outer walls of the leg are provided at points opposite the apertures c of the inner walls with holes or apertures d , which are covered by caps e and screws f , or other suitable 45 fastening devices. By this construction it will be seen that access may be readily had to the water-tubes by simply removing the caps.

E indicates the bridge-wall of the furnace, 50 and F the grate. The bridge-wall is provided transversely in a plane below the grate or leading into the ash-pit with a door h , which

may be closed by an opening g . The plates a and b , which comprise the front water-leg, are cut away at their lower edges or arched, 55 as shown at i , so as to project downwardly or depend on opposite sides of the fire-box, as shown at j , while the plates which comprise the rear water-leg are continued downwardly throughout their width, so as to form a mud-chamber G, which is at a less altitude than the depending portions j of the front water-leg. The outer wall of the rear water-leg is provided with manholes covered by doors k , so as to afford access to the mud-chamber. 60

In stationary boilers, and such as I have here illustrated, the side walls are bricked from the ground-line to the tops of the tubes, as shown at H, and this brickwork extends from the front to the rear water-leg. On the inner 70 side of the brickwork and within the fire-chamber I provide molded fire-brick I, and within the grooves of the fire-brick I place the tubes J, so as to bring them into direct contact with the fire. The tubes J, which are 75 arranged in the fire-box, are of a form similar to the tubes D, although it is preferable to have them of a different diameter, and all of the tubes are disposed in a similar manner and connect the water-legs.

K indicates the lower baffle-plate, and L the upper baffle-plate. These plates are arranged so as to form a tortuous course for the gases and particles of combustion, the upper plate overlapping the lower one and arranged in 85 close proximity to the bottom of the drums.

Arranged upon the lower baffle-plate and contiguous or adjacent to the inner wall of the front water-leg is a perforated steam-box M, and arranged above the upper baffle-plate 90 and contiguous or adjacent to the rear water-leg is a similar box N, which are respectively connected with the steam-drums, as will be presently described.

P indicates the smokestack. This smokestack rises from the boiler near the rear water-leg and is bifurcated so as to straddle the drums and form flues l and m .

Q indicates a plate which forms the inner wall of a part of these flues. This plate is 100 curved for a sufficient width and extends down the outer side of each drum to a point at or about the water-line, and is connected with an inner plate R, which is of a similar form,

and secured directly upon the drum or drums. These plates Q and R are arranged at an interval, so as to form an interspace p, and the inner ends of the respective plates have secured to them a vertical plate q, which is in turn secured to the drums, as shown at r, so as to form spaces s. By this construction it will be seen that the hot gases as they rise will be prevented from coming in contact with the drums at a point above the water-line, and thereby avoid the superheating of the steam.

S indicates a submerged baffle-plate. This plate extends the entire width of the drums and on a plane slightly above that of the feed water-pipe. This plate, which is secured at its outer edge to the inner side of the outer wall of the front water-leg, and after crossing said leg is deflected or bent slightly upward within the drums or drum, as better shown in Figs. 3 and 4 of the drawings. By the employment of this baffle-plate it will be seen that the currents will be prevented from rising within the drums and the foaming of the water be materially reduced. The plates q, which form the outer walls of the spaces or chambers s, also serve to form a central flue t for the smoke and particles of combustion rising from the furnace, so that I have a central flue and two lateral flues for such products. The outer plates or walls of the front and rear water-legs are tied by rods u and v, which extend through the drums and are secured by nuts or other suitable devices.

T indicates the dry-pipe, there being one used for each drum. These pipes, which are of sufficient length, assume a position horizontally within the drums and adjacent to the tops thereof, and are provided on their upper longitudinal sides with perforations w, and their inner ends are also perforated, as shown at y, while their opposite or outer ends U are received in collars V, or the like.

W indicates a manhole in the front water-leg, which is closed by a suitable door, as shown, and this manhole extends into the tube-chamber and at the point where the steam-box M is arranged, so that access may be had to said box as well as to the exterior of the flues.

Numeral 1 indicates a small pipe which taps the outer wall of the rear water-leg and enters one of the drums, and 2 represents a pipe which taps the steam-box N and is connected 55 with the pipe 1 by means of a branch or connection 3.

4 indicates a stop cock or valve for admitting steam from the drum to said steam-box when it is desirable to clean the tubes externally.

5 indicates a small pipe which leads from the other steam-box M and connects by means of a branch pipe 6, which carries a stop cock or valve 7, with the front end of one of the 65 drums, for a similar purpose. It is obvious that when a single drum is used these connections can be made at opposite ends thereof.

8 indicates the feed-water pipes which connect with the pump or injector. These pipes are provided with suitable cocks or valves for opening and closing the same, and said pipes are connected at or near the base of the rear water-leg by means of a transverse pipe 9, and which transverse pipe is connected with the base of said water-leg by means of a branch pipe 10, carrying a stop-cock 11; and leading from this branch pipe is a blow-off pipe 12, which carries a cock or valve 13. This transverse pipe 9 is provided between its point of connection with the base of the water-leg and its connection to the feed-water pipes 8 with check-valves 14, which close to the action of the pump or injector, so as to prevent the water from entering the base or lower portion of the water-leg during the operation of feeding. 85 Rising from these feed-pipes 8 are circulating-pipes 15, which are connected at their upper ends by pipes 16, which pass through the rear water-legs, but without communicating therewith and in a plane slightly below the drums 90 and parallel therewith, or approximately so, and out through the upper portion of the front water-leg, as shown at 17, where they are connected by means of branch pipes 18, carrying check-valves 19, with pipes 20, which are arranged within the drums and have on their discharge ends a funnel 21. By this arrangement of piping for the feed-water it will be seen that I have a thorough system of circulation. When the pump or injector is put into 100 operation and the water enters the pipes 8, it will be prevented from passing into the pipe 9 by reason of the check-valve 14, but will be forced up the pipes 15 to the pipes 17, where it will be brought into direct contact with the 105 heat and particles of combustion passing through the boiler, after which such water will pass through the branches 18 to the pipes 20, where it will be discharged into the drums from the funnels 21. Its course will 110 then be back to the front water-leg, and as the tubes pitch from front to rear the water will pass through the respective flues and into the rear water-leg. As the action of the pump or injector is stopped, the valves 14, 115 which check only to the action of the pump, will, by opening the stop-cock 11, allow the water to pass from the rear water-leg out through the circulating-pipes and back to the drums.

By arching the front water-leg it will be seen that the water-space is extended downwardly on opposite sides of the fire-chamber, and a frame 22, of suitable metal, is placed in this arched portion, which closes the front wall of the fire-box and is flush with the inner wall of the front water-leg. The doors for the fire-box and those for the ash-chamber, respectively, are attached to this plate, as shown.

By making the water-legs and the drums an integral structure and having the end plates or outer plates in one piece and the drums flush with the outer faces of the water-

legs but one throat-plate is necessary, while in a boiler where the water-leg is connected inside or off the head of the drum an opening in the drum would occur, which would require a reinforcing-ring around the opening equal to the sectional area of that part removed, and thereby necessitate the employment of three thicknesses of metal, which would make the joint very rigid and apt to strain the ends of the tubes by the burning and cracking of the plates at the rivet-holes, which is so objectionable in producing leaky joints. When it is desired to clean the tubes externally, it is simply necessary to open the cocks or valves 4 and 7, when steam will be admitted from the drums to the perforated steam-boxes and from there upon the tubes. As a single drum may be employed, I deem it unnecessary to go into a detailed explanation of such construction, as from the description which I have given any one skilled in the art could omit the two drums shown and employ a single one. For marine purposes the brick walls would of course be omitted and sheet-iron siding substituted. A blow-off pipe 22 is attached to the stop-cock 19, as better shown in Fig. 1 of the drawings, and is provided with a valve or cock 23. A valve 24 is also placed in the pipe 18 between the stop-cock 19 and the point 17. This blow-off is for scumming the surface, and is used when the pump or injector is not working. When using this blow-off to scum the surface, the cock or valve 24 should first be closed to prevent the water from coming from the bottom or rear end of the boiler.

Having described my invention, what I claim is—

1. In a steam boiler, the combination of the casing, the smoke stack communicating with the interior of the casing, the drums arranged in the casing on opposite sides of the plane of the smoke stack so as to form a central and side flues communicating with said stack, and plates arranged upon the drums above the water line so as to protect the upper portions of the drums from the heat and particles of combustion passing up the central and side flues, substantially as specified.

2. In a steam boiler, the combination of the casing, the smoke stack communicating with the interior of the casing, the drums arranged in the casing on opposite sides of the plane of the smoke stack so as to form a central and side flues communicating with said stack, the inner and outer plates Q, and R, connected together and to the drums at a point above the water line and having a closed space between them, and the vertical plates V, connected to the plates Q, R, and the drums and serving in conjunction with the drums to form spaces s, all substantially as and for the purpose set forth. 55

3. In a steam boiler, the combination with 65 a drum or drums; of water legs communicating therewith, tubes connecting the legs, baffle plates arranged overlapping each other, the perforated steam boxes arranged transversely above the baffle plates, and valved 70 pipes connecting said boxes with the steam drums, substantially as specified.

4. The combination with a steam boiler, having water legs; of the drums, the feed water pipes, the transverse pipe connecting 75 the same, and having check valves, a connection for said transverse pipe with the lower portion of the rear water leg, pipes passing through the boiler and exterior to the steam drums, pipes connecting the feed pipes therewith, a discharge feed pipe entering the drums from said circulating pipes, substantially as specified. 80

5. In a steam boiler, the combination with the water legs and drums; of the feed water 85 pipes, the pipe arranged in the drums and having the funnel discharge, the circulating pipes connecting said feed pipe with the discharge pipe, the pipe connecting said pipes with the lower portion of the rear water leg, suitable 90 cocks or valves in said pipes, and the baffle pipes arranged in the drums, substantially as specified.

In testimony whereof I affix my signature in presence of two witnesses.

JOHN HAZLETT.
